UNITED STATES PATENT OFFICE.

LEVI K. FULLER, OF BRATTLEBOROUGH, VERMONT, ASSIGNOR TO THE
ESTEY ORGAN COMPANY, OF SAME PLACE.

DESIGN FOR AN ORGAN-CASE.

SPECIFICATION forming part of Design No. 15,432, dated October 7, 1884.

Application filed May 31, 1884. Term of patent 14 years.

To all whom it may concern:

Be it known that I, LEVI K. FULLER, a citizen of the United States, and a resident of Brattleborough, Windham county, Vermont, have invented or produced a new and original Design for an Organ-Case, of which the following is a specification.

My design is clearly shown in the accompanying photographic illustration, in which A designates the front board of the case; B, the key-board projection; C, an open-work panel above the stop-board; D, the back board of the case, and E the ends. The front board A is divided, as usual, into three panels, *a a a*, which are ornamented as follows: The middle panel has a series of horizontal parallel lines, on one of which is a horizontal row of three bosses. The side panels are alike, and each is ornamented with two bosses, arranged one above the other in the center of the panel. The front of the key-board projection B is provided, as usual, with an open-work strip. This form of one or two elongated openings, filled in with end ornaments consisting of obliquely-crossed bars, and central ornaments consisting of two vertical cross-bars, a horizontal bar with rounded ends arranged across the latter, and short vertical bars or billets arranged across the horizontal bar, all of which is clearly shown in the accompanying photograph. The open-work panel C is slightly inclined and formed of several rectangular openings, some of which are crossed diagonally by bars. Some have each a horizontal bar with rounded ends crossed by short billets, and one, in the center, has four bars extending in from the sides of the rectangle and crossing each other in such a manner as to form a small central square. This design harmonizes with that in the open-work strip in B, and is so clearly shown in the photograph as to require no more minute description. The back board, D, rises above the ends of the case, and is divided into three portions, *b c c*, which I call "panels." The central panel, *b*, rises above the side panels, as is common in such designs, and it has a canopy-like projection, *d*, at the top, ornamented with an indented drop-cornice, a scalloped-edged frontispiece, *e*, and

scallop-edged corner ornaments, *f*. At its base 50 the panel *b* has a pocket-like projection, the front board *g* of which has an indented upper edge of the same design as the drop-cornice above it, and open-work formed of three rectangular openings, the end ones crossed by obliquely-arranged bars, and the center one crossed by a horizontal bar with rounded ends, which bar is crossed vertically by short billets. This design, which is clearly shown in the accompanying photograph, is very similar 55 in its elements to that of panel C. The face of the panel *b* is ornamented by two vertical and two horizontal lines arranged near the edges of the same and crossing each other. The side panels, *c*, are alike in design, and a 60 description of one will suffice. Across the top of the panel is a horizontal bar, *h*, ornamented by lines at its edges, and the face of the panel is ornamented by vertical and horizontal cross-lines similar to those on the central panel, *b*. On the bar *h* is mounted a fan ornament, *i*, the edge of which is indented after the same design as that of the drop-cornice on *d*, and on its face are horizontal lines 65 at the base and a series of concentric semicircular lines. Under this fan ornament are four baluster-like posts, as clearly shown in the accompanying photograph. At the back corners of the case are posts *j j*, each ornamented with a boss, and on the ends of the case are 70 like corner pieces *k k*, having an ornamental contour, and each provided with an ornamental knob, as clearly shown.

Having thus described my invention, I claim—

1. In an organ-case, the design which consists of a front board A, divided into three panels, *a a a*, the middle panel ornamented by a series of horizontal lines, on one of which are three bosses, and the side panels ornamented each with a vertical row of bosses, substantially as shown in the accompanying photograph.

2. In an organ-case, the design which consists of an open-work strip in the front of the key-board projection B, the ornamentation in said strip comprising an elongated opening with diagonally-set crossed bars at its ends, two

(OVER)

vertical bars, a horizontal bar with rounded ends crossing the vertical bars, and a series of short billets crossing the horizontal bar, substantially as shown in the accompanying photograph.

5. In an organ-case, the design which consists of the ornamentation of the canopy-like projection *d*, and the pocket-like projection *g* at the base of the canopy, as shown in the accompanying photograph.

10. In an organ-case, the design which consists of a central panel, *b*, in the elevated back board, having a canopy-like projection, *d*, at its top, and a pocket-like projection, *g*, at its base ornamented with an open-work front

board, as shown, the like side panels, *c*, having fan ornaments *i*, under which are baluster-like ornaments, the bossed corner posts, *j*, and the corner pieces, *k*, having an ornamental configuration and ornamental knobs, one on each, substantially as shown in the accompanying photograph. ²⁰

In witness whereof I have hereunto signed my name in the presence of two subscribing witnesses.

LEVI K. FULLER.
